UNITED STATES PATENT OFFICE.

WILLIAM R. SANTLEY, OF WELLINGTON, OHIO.

MACHINE-BELT HOLDER.

SPECIFICATION forming part of Letters Patent No. 298,238, dated May 6, 1884.

Application filed October 5, 1883. (No model.)

To all whom it may concern:

Be it known that I, WILLIAM R. SANTLEY, of Wellington, in the county of Lorain and State of Ohio, have invented a certain Improved Machine-Belt Holder; and I do hereby declare the following to be a full and complete description thereof.

The said invention relates to a machine-belt holder upon which a belt is shifted from a live pulley or drum and held in a slackened state at rest when not required for use.

The invention consists of a differential curved or segmental rim, in the face of which are transverse slots or openings for rollers, which have their pivotal or axial supports in projections from the said rim. To the interior face of the rim is attached one or more braces, which may be arranged in sections for supporting and strengthening the rim with the rollers.

The belt-holder herein set forth may be held and sustained in relation to a driving-pulley in any suitable position and by ordinary means without departing from the nature of the said invention.

For a more full and complete description of the construction and operation of the said belt-holder reference will be had to the following specification, and to the annexed drawings, making part of the same, in which—

Figure 1 is a face or front view of the holder; Fig. 2, a side view, and Fig. 3 an inside view of the said holder opposite to that of Fig. 1.

Like letters denote like parts in the several drawings.

The said invention is supported in position at the side of a live pulley or drum upon a line of shafts, and so arranged that the belt may be shifted from the pulley or drum, when not in use, onto the holder, and then slackened and at rest, thereby preserving the belt from needless wear and strain, and a relaxation of the belt-tension from the strain when upon the live-pulley. The holder may be of any desirable size to correspond with and according to the diameter of the pulley for which it is designed.

In the rim A are a series of transverse slots, B, in which are rollers C, having pivots

or shafts D, Fig. 1, and are pivoted or journaled in the arms or projections E, extending from the interior face or edge of the rim A on both sides, as seen in Figs. 2 and 3. In place of said arms, a continuous flange may be made to extend along the length of the rim A on both sides, in which the roller bearings or pivots can be supported in line with the slots B, essentially the same as when journaled in the arms or ears E. The rim of the holder is formed in differential curves or segments. From a to b is the segment of the pulley-circle, and from b to c is less than from a to b, or converges toward the axis of the rim. By this construction the belt will be slackened when shifted upon the rim A from the live-pulley, as the holder is placed in such close proximity to the pulley as to be readily shifted from one to the other by the ordinary devices and mechanism used for shifting belts. The rim A is stiffened and strengthened by means of one or more stays or plates, F, Figs. 2 and 3, firmly attached to the interior face of the said rim, and connected with suitable means for supporting the holder in juxtaposition with the driving-pulley or drum.

In place of the brace or braces F, a frame or series of arms may be arranged in connection with the rim for strengthening and securing the holder in its place.

No especial means are required to sustain the holder in its relation to a live pulley or drum, as its construction and arrangement admit of various devices and means for this purpose.

The holder may be firmly held adjoining a driving-pulley or drum by braces, frame-work, or iron stays.

The manner and appliances required for sustaining the holder admits of such modifications as may be needed in adapting it to various positions without departing from the nature of the invention.

What I claim as my improvement, and desire to secure by Letters Patent, is—

1. A machine-belt holder consisting of a combination of the rim A, having a differential peripheral curve, and transversely in the face thereof a series of slots, rollers journaled

in said slots in suitable bearings at each end thereof, and so adjusted that the face of the rollers may be above the surface of the rim, and one or more re-enforcing plates or braces 5 within the rim, substantially as herein set forth.

2. In combination with a series of rollers, C, arranged within slots of the rim A, one or more braces or plates secured to the inner

face of said rim, substantially as and for the purpose set forth.

In testimony whereof I affix my signature in presence of two witnesses.

WILLIAM R. SANTLEY.
